UNITED STATES PATENT OFFICE.

EDWIN M. CROSS, OF SYRACUSE, NEW YORK.

BELTING.

SPECIFICATION forming part of Letters Patent No. 274,280, dated March 20, 1883.

Application filed February 1, 1883. (No model.)

To all whom it may concern:

Be it known that I, EDWIN M. CROSS, of Syracuse, in the county of Onondaga, in the State of New York, have invented new and useful Improvements in Belting, of which the following, taken in connection with the accompanying drawings, is a full, clear, and exact description.

It is a well-known fact to mechanical engineers and machinists that the ordinary belting at present in the market will, after a short usage, stretch, so as to lose its frictional hold on the pulleys, and requires frequent tightening. This defect has in many instances led to the employment of double belts. These, however, are more expensive, and do not afford a strength proportionate to the quantity of material, owing to the difference in the lengths of the inner and outer layer of material when stretched on two pulleys, and the consequent unequal strain on said layers of material.

Manufacturers of belts have attempted to take the stretch out of the belting by subjecting it to a stretching-machine; but this treatment has only replaced the aforesaid defects by other and more serious defects—viz., it frequently weakened the belting by excessive strain of its fibers, and when such belting is applied to use it almost invariably twists and warps, so as to deprive it of an effective hold on the pulley and of its capacity of tracking truly.

Attempts have been made to re-enforce single-thick belting by the use of strands of wire stretched along the surface of the belting, and fastened thereto at intervals; but it is obvious that such construction does not combine the wire with the belt in such a manner as to impart to the belt the desired stability.

It is to obviate the aforesaid defects by simple and comparatively inexpensive means which my invention has for its object; and to that end it consists essentially in stitching a single-thick belt longitudinally with waxed or metallic thread.

In leather belts one row of stitches near each edge thereof, as shown in Figure 1 of the drawings, is in many cases sufficient. Canvas and rubber belts, however, should be provided with additional rows of stitches between those at the edges of the belt, as shown in Fig. 2 of the drawings.

In Fig. 3 is shown a longitudinal section of the belt, taken on the line of one of the rows

of stitches designated by the reference-letters *a a*. A leather belt thus made requires no preliminary stretching, but its fibers are left intact and unimpaired, and whether the belt is composed of leather, canvas, rubber, or other equivalent material, it is so're-enforced by the described sewing as to relieve the fibers of the material of the greater portion of the strain, effectually prevent the stretching of the belt, and render one edge thereof as strong as the other, thus causing said belt to invariably track true and retain its efficiency. In fact, said sewing imparts to the single belt a strength equal to that of the double belts now in use. Furthermore, a single beltstitched near the edges in the manner shown and described stiffens the edges thereof, so that when said belt is applied to cone-pulleys the edges of the belt are capable of resisting the outward or upward pull incident to their frictional contact with the adjacent vertical face of the pulley.

When my improved belting is made of leather, any portion of the hide can be used. Experience has proved that a belt made from the flank or spongy portion of the hide is as strong and effective as one made from the center of the hide.

I am aware that belts of two or more thicknesses of leather and of other material have been sewed longitudinally; but such sewing was applied merely for the purpose of uniting the several layers of material, and, owing to the unequal distribution of the strain on the several layers or thicknesses of the belt, as before stated, the sewing of such belting cannot produce the effect derived when applied to a single thick belt.

Having described my invention, what I claim as new, and desire to secure by Letters Patent, is—

As an improved article of manufacture, a single-thick belt re-enforced by longitudinal rows of stitches of waxed or metallic thread extending the length of the belt, substantially as described and shown.

In testimony whereof I have hereunto signed my name and affixed my seal, in the presence of two attesting witnesses, at Syracuse, in the county of Onondaga, in the State of New York, this 30th day of January, 1883.

EDWIN M. CROSS. [L. S.]
